UNITED STATES PATENT OFFICE.

MARK H. MILLER, OF INDIANAPOLIS, INDIANA.

VENTILATING APPARATUS.

Application filed August 26, 1926. Serial No. 131,608.

This invention is a ventilating screen construction that is translucent but not transparent. In other words, it permits the passage of air and sunlight, but not enough light 5 to enable one to see objects through it.

The invention is designed for window screens and ventilating apparatus in hotels, apartment houses, tenement houses, and like 10 places where people need ventilating means 10 which will not be transparent.

The chief feature of the invention consists 15 in providing a plurality of pairs of obliquely placed screens, one pair spaced above another so that the lower edge of each oblique screen 15 of each pair will be substantially in the same plane as the upper edge of the adjacent pairs of screens or overlap slightly, and there will be ample space between the two pairs of screens for the passage of air.

20 Another feature of the invention consists in combining with the above a centrally-located vertically-removable screen made of wire netting, cloth or other reticulated frame or fabric through which air can pass.

25 It is thus apparent that such ventilating construction can be used as window screens in residences, hotels, apartment and tenement houses and can also be used for the ventilation of interior rooms, corridors and the like 30 so as to provide ample ventilation and yet fully protect the occupants of the room or building from being seen by anybody outside.

The device also screens out insects, flies, 35 etc., during the summer and acts as an air filter during the winter and effectually diverts rain, although permitting ventilation.

The full nature of the invention will be understood from the accompanying drawings 40 and the following description and claim:

In the drawings, Figure 1 is a front elevation of a window frame with such ventilating screen therein. Fig. 2 is a central vertical section through the same. Fig. 3 is a part of 45 what is shown in Fig. 2 on an enlarged scale. Fig. 4 is a section on the line 4—4 of Fig. 3 through a portion of an angular screen. Fig. 5 is a plan view of a portion of an angular screen. Fig. 6 is a horizontal section at the 50 top of the screen construction and showing the latter in plan.

There is shown in the drawings a window frame 10 and a ventilating screen mounted therein. The ventilating screen when constructed as shown has a sheet metal plate 15 removably and slidably mounted adjacent

the side of the window frame. It is vertically slidable thereon by means shown in Fig. 6, where the screen frame 15 is bent A-shaped at 20 to enter and slide in a 60 W-shaped vertical guide 21 that is secured to the side of the window frame. The screen frame or plate 15 is made of metal and has two vertical series of tongue plates 14 punched out of the same, as shown in Figs. 65 3 and 4, to which the ends of the wire or other screens 12 are secured by the rivets 26. These tongues 14 and screens 12 are arranged obliquely to a vertical line, as seen in Fig. 3, and they are arranged in pairs, one 70 pair located above another, as there shown, the two pairs being A-shaped and the lower end of each pair of screens extending on a line with or overlapping the upper end of the next pair of screens below. These screens 75 are herein termed "angular" screens and are arranged at an angle of about 45 degrees from the perpendicular.

The screens can be inserted in windows or 80 walls and be slidable in the windows as described, the particular arrangements for such mounting not being very material to this invention and not being described more fully. The angular screens may be made of any translucent glass or water proof wire 85 screen so that the rain will be deflected and diverted thereby from entering the room even if the window be open and also the screens will be translucent, but they will not be sufficiently transparent to enable one 90 from the outside to see an object through the same.

Another feature of the invention consists in combining with the foregoing described screen construction a vertical screen 11 that 95 has a frame 16 which is insertable in and removable from said previously described screen construction. This may be accomplished by providing a guideway 22 in the side frame plate 15 of the angular screen construction heretofore described, as shown in Figs. 3 and 6, although the invention is not limited to this construction for the introduction of the vertical screen. While the vertical screen is shown provided with wire 100 netting 11, which is desirable in the summer time, in the winter time a cloth screen may be used instead of that shown so that it will filter the air as well as permit the passage of air through it. This vertical screen can 105 be made of any suitable material, whether cloth or wire netting, according to the im-

mediate need. The screens or shutters 12 are not limited to any particular material, but may be made of any material desired.

The bottom plate of the frame 15 is provided with a central slot 17 through which the screen 11 and its frame 16 is insertable and removable. Said screen and its frame are held in place by the locking lug 18 pivoted to the plate of the frame 15 at 19, so that it may be moved in and out of locking position. Thus, one type of screen may be readily substituted for another when desired, or removed for any other purpose, such as cleaning or the like, and replaced.

15 The invention claimed is:

Ventilating means including a frame having an opening in the lower part thereof, a vertical series of angular screens secured within said frame arranged in substantially

20 A-shaped pairs, said screens being formed

of a translucent but non-transparent material for permitting the passage of light while preventing vision therethrough, the pairs of screens being spaced from each other vertically so that the lower edges of each pair of screens will extend down at least to the same plane as the upper edges of the pair of screens below so as to permit the free passage of air while preventing the passage of the elements, a vertical screen insertable in and removably mounted through the opening in said frame between each series of angular screens, and a latch secured to the lower portion of said frame adjacent the opening therein for locking said vertical screen therein.
